UNITED STATES PATENT OFFICE.

CORNELIUS D. EHRET, OF PHILADELPHIA, PENNSYLVANIA.

ELECTRICAL WAVE TRANSMISSION.

1,400,591.

Specification of Letters Patent. Patented Dec. 20, 1921.

Application filed March 12, 1919. Serial No. 282,166.

To all whom it may concern:

Be it known that I, CORNELIUS D. EHRET, a citizen of the United States, residing in the city and county of Philadelphia, State 5 of Pennsylvania, have invented a new and useful Electrical Wave Transmission, of which the following is a specification.

My invention relates to a method of and apparatus for electrically transmitting 10 speech by recourse to carrier waves both in systems where the energy of those waves is radiated or otherwise transmitted through the natural media, and where the carrier wave is in the form of a current transmitted 15 over a conductor or conductors extending between the transmitting and receiving stations.

My invention resides in a method of and apparatus or system for electrically transmitting 20 speech, or sound waves in general, wherein energy modulated in accordance with sound waves or speech is impressed upon the plate or anode circuits of a thermionic oscillation producing means, whereby 25 different groups of high frequency oscillations or carrier waves are produced whose amplitude varies in accordance with the speech or sound waves, the envelop of the successive groups representing the complete 30 message, such energy being supplied as the plate or anode circuit energy in the absence of and as distinguished from the usual direct current source employed for energizing the plate or anode circuit.

By such method and apparatus no high 35 frequency or carrier wave energy is radiated or impressed upon the line conductor until the existence of speech or sound waves; that is to say, no high frequency energy 40 comes into existence or is radiated or impressed upon the line conductor until the microphone is actuated by speech or other sound waves.

My invention resides further in a method 45 and apparatus or system of the character referred to, wherein the telephonic current is first amplified before conversion into the high frequency carrier wave energy.

My invention resides further in a method 50 and apparatus or system of the character referred to in which the high frequency or carrier wave energy produced as described is amplified before radiation thereof into the natural media or impression thereof on a 55 line conductor.

My invention resides further in a method and apparatus or system of the character referred to wherein high frequency current modulated in accordance with speech or sound waves is converted into high frequency or carrier wave energy of different, 60 preferably higher, frequency.

For an understanding of my method and for an illustration of some of the various forms my apparatus may take, reference is 65 to be had to the accompanying drawing, in which:

Figure 1 is a diagrammatic view of apparatus embodying my invention and suitable 70 for carrying out my method.

Fig. 2 is a diagrammatic view of a modified form of apparatus suitable for a simplified method of carrying out my invention.

Fig. 3 is a diagrammatic view of a modified form of apparatus embodying my invention and suitable for carrying out my method. 75

Referring to Fig. 1, a microphone *m* is connected in circuit with a suitable source of current, as a battery *a*, in the primary of a transformer *t* whose secondary is connected directly to the circuit of the grid *g* of an amplifier *A* of suitable type, in this instance of thermionic type having in association with the grid *g* the anode or plate *p* and the 80 filament or cathode *f* rendered incandescent by current from the battery *b*. In the grid circuit may be included if desired or suitable, a device *c* which may be either a condenser or a battery, as well understood in 85 the art. In the plate circuit of the amplifier is the battery *d* and the primary of a transformer *t*₁ of any suitable ratio of transformation, but preferably a step-up transformer delivering current at potential high 90 enough, as regards the smallest amplitude of the voice current it is desired shall be transmitted, to equal and preferably exceed the lowest potential suitable for operating the anode circuits of the oscillator *O*. The 100 opposite ends of the transformer secondary are connected, respectively, to the plates or anodes *p*₁ and *p*₂ of a thermionic oscillator *O* comprising, in addition, the grid *g* and incandescent filament or cathode *f*. Connected across the secondary of the transformer *t*₁ are the condensers *C*₁ and *C*₂, 105 preferably variable to attain equal capacity, or, in any event, to cause oscillations of the same frequency in and by coöperation with 110

110

the inductance L , whose one terminal connects to a point between the condensers C_1 and C_2 and to a variable mid-point on the secondary of the transformer t_1 , and whose 5 other terminal is variable and connected to the filament f . The grid circuit is coupled to part of the inductance L by the variable inductance l . In the grid circuit may be employed if suitable or desirable a condenser c .

In inductive relation with the inductance L is the variable transformer secondary L_1 whose one terminal connects through the variable non-inductive resistance r , which 15 may be adjusted to suitable value or which may be entirely cut out, to the grids g , g of the high power amplifiers A_1 , A_1 , any number of which may be connected in parallel with each other as indicated, as by 20 parallel connection of their plates, grids and filaments. For energizing the plate circuits may be provided the battery or other source of current d_1 , and in the grid circuits may be connected the battery b_1 with its negative 25 terminal presented to the grids. Connected across the grid circuit, upon closure of the switch e , is a variable condenser C_3 for tuning the grid circuit to the frequency of the oscillations derived from the secondary L_1 . 30 However, it will be understood that either or both the condenser C_3 and the resistance r may be omitted. The plate circuit of the amplifiers A_1 , A_1 includes the adjustable transformer primary L_3 , in circuit with 35 which may be the adjustable condenser C_4 , for tuning the plate circuit to the frequency of the amplified oscillations, if such tuning is desired. Inductively associated with the primary L_3 is the adjustable secondary L_4 40 whose one terminal may be connected to earth E , and whose other terminal may be connected through an adjustable inductance L_5 to the antenna or radiating structure R of a radio system. Or the transformer secondary L_4 may connect to any suitable line 45 conductor or line conductor system extending between transmitting and receiving stations.

The operation is as follows:

50 Uttering speech or sound waves against the microphone m varies the current from the battery a , and the resultant current having sound wave or speech modulation is transformed by the transformer t and delivered to the amplifying apparatus A , which amplifies the telephonic energy to any suitable degree. For this purpose a plurality of amplifier devices A may be employed, either in parallel or in cascade. 55 The amplified energy is then impressed by transformer t_1 upon the anode or plate circuits of the oscillator O , with the result that all the undulations or frequencies of positive sign or polarity from the secondary of 60 the transformer t_1 are converted by one of

the anode circuits, for example, that including anode p_1 , into high frequency oscillations, for example, 10,000 per second upwardly to 20,000 per second or more for carrier wave conductor systems and 10,000 70 cycles per second upwardly to 500,000 cycles per second, or more, for radio systems. Similarly, the energy of negative sign or polarity and of varying or telephonic frequency is converted into oscillations, preferably of the same frequency, by the anode circuit including the anode p_2 .

Thus there are directly produced by conversion of the amplified telephonic energy high frequency oscillations varying in amplitude in accordance with speech or sound waves, the telephonic energy being the only energy supplied to the plate or anode circuits, as distinguished from the ordinary case where a battery or the like is in the 80 anode or plate circuit and the telephonic energy employed merely to vary the potential of the grid of the thermionic oscillator.

With an oscillator which employs a battery or the like in the plate circuit, with the potential of the grid altered in accordance with speech to vary the amplitude of the oscillations produced from energy of the battery, oscillations are continuously produced without regard to the fact whether 90 or not speech or sound waves are being uttered against the microphone which controls the potential of the grid; and in a system employing such an oscillator the high frequency oscillations or carrier wave is being continuously radiated or impressed upon the line conductor.

By my method and apparatus, however, as described, the high frequency oscillations are not existent or produced except when the 105 microphone is actuated.

The oscillations so produced directly by conversion from the telephonic energy are then suitably amplified, if desired, to practically any power; and as such impressed 110 upon the radiating system R of a radio system or analogous system employing the natural media, or upon a line conductor extending to the receiving station.

It will be understood that the amplifier 115 A may be omitted; and it will be understood also that the amplifiers A_1 , A_1 may be omitted.

The omission of these amplifiers is indicated in Fig. 2, where with the inductance L of the oscillator O is associated the variable inductance L_4 , which may be connected to a line conductor in a conduction system, or which, as indicated, may be connected to earth E and through variable inductance L_5 120 to the radiating structure or conductor R .

In Fig. 3 between the transformer t and the oscillator O intervenes a second oscillator O_1 of a known type employing in its plate circuit a battery d , which supplies the 130

energy for the oscillations, the potential of the grid being controlled by the microphone m in usual manner. The grid circuit is coupled in known manner to the plate circuit, variable condensers C_5 and C_6 being employed to determine the frequency of or attune the plate and grid circuits. In the primary of the transformer t_1 there accordingly occur high frequency oscillations of predetermined frequency, the amplitude being modulated by the microphone m through the potential control of the grid g or oscillator O_1 . These high frequency oscillations are then transmitted through the transformer t_1 to the oscillator O , wherein the half waves or oscillations of positive sign are converted into high frequency oscillations of the same or different frequency, higher or lower, in the circuit of one of the anodes, as p_1 , while the half waves or oscillations of negative sign are converted into oscillations of such different frequency in the circuit of the anode p_2 . The energy of the oscillations of this second frequency, which also are modulated in accordance with the sound waves or speech uttered against microphone m , are impressed through transformer L , L_4 either upon a line conductor or upon the radiating system or structure R . For example, the frequency of the oscillations produced by oscillator O_1 may be 10,000, 20,000 or 30,000 cycles per second, or more or less, while the frequency of the oscillations produced by the oscillator O may be any suitable higher frequency, for example, upwardly to 500,000 cycles per second, or more.

Of Figs. 1 and 2, it is characteristic that in the anode or plate circuits of the oscillator O no battery or other source of energy is present which, if present, would cause continuous production of oscillations, whether or not the microphone m were actuated or in operation. The oscillator O in each of these cases produces oscillations only when the microphone m is actuated.

In the case of Fig. 3, however, the oscillator O_1 will continuously produce oscillations, whether or not the microphone m is actuated, and these oscillations will be converted in the oscillator O into oscillations of different frequency, which will continuously be radiated from the structure R or impressed upon a line conductor; but these last named oscillations will not be modulated in

accordance with speech until the microphone m is actuated by speech or sound waves, or other means.

What I claim is:

1. The combination with a thermionic oscillator comprising anodes, a transformer secondary connected thereto, grid structure and an electron-emitting body, inductance and capacities in the circuits of said anodes, a coupling between the circuit of the grid structure and the anode circuits, said capacities connected in series across said secondary, a connection from between said capacities to said inductance, and means supplying modulated energy to said transformer including a source of continuous current, and means controlling the current of said source in accordance with sound waves.

2. A thermionic oscillator producing oscillations varying in amplitude in accordance with sound waves, comprising anodes, grid structure and electron-emitting means, a source of current representing sound waves, the terminals of said source connected, respectively, to said anodes, capacities in series with each other bridged across said anodes, a connection from a point between said capacities to a point intermediate the terminals of said source, and means coupling the anode and grid circuits.

3. Thermionic oscillation-producing means comprising a source of current representing sound waves, anodes connected to the different terminals of said source, grid structure, electron-emitting means, an inductance comprised in a coupling between the anode and grid circuits, capacities in series with each other bridged across said anodes, and a connection from a point intermediate the terminals of said source and a point between said capacities to said inductance, said source constituting the only source of current in each of said anode circuits.

4. Thermionic oscillation-producing means comprising a source of current representing sound waves, anodes connected to the different terminals of said source, grid structure, electron-emitting means, a connection from said electron-emitting means to a point intermediate said terminals of said source, and means coupling the anode and grid circuits.

In testimony whereof I have hereunto affixed my signature this 11th day of March, 1919.

CORNELIUS D. EHRET.
